DESIGN FOR A BOTTLE

Laurence J. Colwell, New York, N. Y., assignor to Charles of The Ritz, Inc., New York, N. Y., a corporation of Delaware

Application March 18, 1947, Serial No. 137,692

Term of patent 14 years

(Cl. D58—6)

To all whom it may concern:

Be it known that I, Laurence J. Colwell, a citizen of the United States, residing at New York city, in the county of New York and State of New York, have invented a new, original, and ornamental Design for a Bottle, of which the following is a specification, reference being had to the accompanying drawing, forming part thereof.

In the drawing:

Fig. 1 is a front elevational view of a bottle, showing my new design;

Fig. 2 is a rear elevational view thereof, and

Fig. 3 is a bottom plan view of my design.

I claim:

The ornamental design for a bottle, substantially as shown.

LAURENCE J. COLWELL.
